UNITED STATES PATENT OFFICE.

WILHELM WEBER, OF HAYINGEN, GERMANY.

BLASTING-CARTRIDGE.

1,226,833.

Specification of Letters Patent. Patented May 22, 1917.

Application filed October 1, 1915. Serial No. 53,479.

To all whom it may concern:

Be it known that I, WILHELM WEBER, a subject of the German Emperor, residing at Hayingen, Lorraine, Germany, have invented new and useful Improvements in Blasting-Cartridges, of which the following is a specification.

This invention relates to blasting cartridges consisting of a combustible metallic powder, an absorptive substance for liquid air, and a primer.

In another application for a patent I have described an improved blasting cartridge which is ignitable by means of a primer and consists of a combustible metallic powder and an absorbtive for liquid air, the absorbtive being an organic substance of great absorptive power, and the combustible metallic powder is separately disposed from the absorbtive. These compounds of a blasting charge are placed into a cartridge which may be introduced into the bore-hole, as is more fully described in my said other application. The primer by means of which the blasting charge is exploded must be placed in contact with the metallic powder.

The object of my present invention is to improve upon such a cartridge in order to produce, during the ignition of the blasting compound, a larger quantity of heat and in consequence a more intense blasting action. With this object in view I have discovered that it is advisable to employ several kinds of combustible metallic powders instead of a single metallic powder. As suitable metals the following may be employed: aluminum, antimony, magnesium, and the like.

These metallic powders are wrapped into a bag and may be mixed with some quantity of an organic substance, or amorphous carbon, in order to obtain a more effective dispersion, within the metallic powders, of a part of the liquid air, or liquid oxygen, contained in the cartridge. This organic substance, or carbonized organic substance, mixed with the combustible metallic powders, absorbs liquid air, enriched with oxygen, from a storage vessel for liquid air, which may be provided in the cartridge as I have described in my aforementioned application, or else the liquid air

is drawn from the saturated mass surrounding the bag.

To further enhance a quick development of heat, the latter mass surrounding the bag may also consist of carbonized organic substance possessing a great power of absorption for liquid air.

The accompanying drawing represents a longitudinal section of a blasting cartridge embodying my invention.

The cartridge consists of a casing *h*, a perforated tube *i* placed in the center thereof, a primer *k* embedded in the combustible metallic powder *b*, a substance *l* to be saturated with liquid air, and a stopper *s* for the tube *i*.

I wish it to be understood that while I have specified some metals as being especially suitable for the purpose described, my present invention is not limited to the application of the metals specified.

What I claim is:—

1. A blasting cartridge adapted to be saturated with liquid air and ignited by means of a primer, comprising, in combination, a combustible organic substance, and a mixture of combustible metallic powders disposed separately from said combustible organic substance.

2. A blasting cartridge adapted to be saturated with liquid air and ignited by means of a primer, comprising, in combination, a combustible organic absorbtive for liquid air, and a mixture of metallic powders inclosed so as to be separated from said organic absorbtive.

3. A blasting cartridge adapted to be saturated with liquid air and ignited by means of a primer, comprising, in combination, a combustible organic absorbtive for liquid air, and a mixture of combustible metallic powders with an organic substance, said mixture being inclosed so as to be separated from said combustible organic absorbtive.

4. A blasting cartridge adapted to be saturated with liquid air and ignited by means of a primer, comprising, in combination, an organic absorbtive for liquid air, and a mixture of metallic powders with a carbonized organic substance, said mixture being placed in a bag whereby a separation of said combustible metallic powders from said absorbtive for liquid air is obtained.

5. A blasting cartridge adapted to be saturated with liquid air and ignited by means of a primer, comprising, in combination, a carbonized organic substance adapted to act as an absorbent for liquid air, and a mixture of metallic powders with a carbonized organic substance, said mixture being

wrapped up so as to be separated from said first-named carbonized organic substance.

WILHELM WEBER.
